The ornamental design for a barrel, as shown and described.

DESCRIPTION

FIG. 1 is a top plan view of a barrel showing the new design; FIG. 2 is a side elevational view thereof;

FIG. 3 is a cross sectional view thereof taken along line 3—3 of FIG. 1; and,

FIG. 4 is a detail thereof taken from area 4 of FIG. 3. The bottom follows the contours shown in FIG. 3, which are uniform throughout.
